Ernest E. Keddy
his ATTORNEY

UNITED STATES PATENT OFFICE.

DANIEL A. CRAUN, OF ORANGE, VIRGINIA.

PIN-INSERTING TOOL.

Application filed March 7, 1922. Serial No. 541,718.

To all whom it may concern:

Be it known that I, DANIEL A. CRAUN, a citizen of the United States, residing at Orange, in the county of Orange and State 5 of Virginia, have invented certain new and useful improvements in Pin-Inserting Tools, of which the following is a specification.

My invention relates to an improvement in pin inserting tools.

10 In some automobiles, especially the Ford, much difficulty is encountered in inserting the pin in the valve-stem, owing to its rather inaccessible location, and, besides this, difficulties are presented in inserting this pin 15 just the right distance.

It is the object of this invention to overcome those difficulties successfully.

20 My present invention consists of a tube and a rod slidable therein, with means for gauging the extent of projection of the rod to correspond to the size of pin to be inserted 25 in the valve-stem.

In the accompanying drawings:

Fig. 1 is a section showing the parts in 30 their normal position, with the pin inserted in the end of the tool;

Fig. 2 shows the position of parts when the pin has been properly inserted in the valve-stem.

35 A, represents the tube, and 1 is the rod fitted to and slidable in the bore of the tube. This rod has a handle 2 secured to one end, and a spring 3 sleeved around the stem of the handle presses outwardly normally to withdraw the rod 1 to its normal position, as shown in Fig. 1. When so withdrawn, it 40 forms a socket at the end of the tool to receive the major portion of the pin 4, with one end slightly protruding. This facilitates inserting the pin in the hole 5 of the valve-stem 6.

In inserting the pin, the head 7 on the end of the handle is placed in the bottom of the hand, and the first two fingers grasp 45 the flange 8 of the sleeve 9.

The tool is then aimed so that the protruding end of the pin 4 is inserted in the hole 5 of the valve stem, whereupon the operator presses against the head 7, pressing the spring 3 and forcing the rod 1 through the tube just the correct distance to insert the pin 4, so that the opposite ends project an equal distance beyond the sides of the valve-stem.

To gauge accurately the inserting of the pin as above explained, a threaded nipple 10 screws into the threads 11 of the sleeve 9. In the drawing, this is shown screwed into the sleeve its full length, and the shank of the handle in Fig. 2 is shown pushed in 55 as far as it will go; but, should the pin be of greater length, the parts are adjusted thereto by turning the threaded nipple 10 to the left, or unscrewing it part way, or in other words a distance corresponding with 60 the length of the pin. For different sized pins, a different size tool is employed, but the parts may be all precisely the same, except in size.

65 In this way, a very simple tool for a special purpose is provided, thus saving much time, annoyance, and expense hitherto encountered in inserting the pin in the valve-stem.

I claim:

70 1. A tool of the character described, including a tube, a rod slidable therein, and a threaded nipple serving as a gauge to regulate and determine the extent of slide of the rod.

75 2. A tool of the character described, including a tube, a rod slidable therein, a threaded nipple serving as a gauge to regulate and determine the extent of slide of the rod, and a spring which, when released, returns the rod to its normal position in the tube.

80 85 In testimony whereof I affix my signature.

DANIEL A. CRAUN.
